(57) **CLAIM**

The ornamental design for a priming knife as shown and described.

DESCRIPTION

FIG. 1 is a side view of a priming knife, showing my new design;

FIG. 2 is a top view (blade down) thereof;

FIG. 3 is an end view (from the handle) thereof; and,

FIG. 4 is an end view (from the tip of the blade) thereof. The broken lines are shown for the purpose of illustrating parts of the article that form no part of the claimed design.
